UNITED STATES PATENT OFFICE.

JESS A. MORRISON, OF SALT CREEK, WYOMING, AND WILLIAM W. HARGROVE, OF BOULDER, COLORADO.

WELL-CASING COLLAR.

Application filed April 19, 1923. Serial No. 633,259.

To all whom it may concern:

Be it known that we, JESS A. MORRISON and WILLIAM W. HARGROVE, citizens of the United States, residing at Salt Creek and 5 Boulder, in the counties of Natrona and Boulder and States of Wyoming and Colorado, have invented certain new and useful Improvements in Well-Casing Collars, of which the following is a specification.

10 This invention has to do with oil well or like well sinking operations, in that it provides an attachment in the form of a casing collar susceptible of being applied temporarily to the upper end of the last length 15 or section of the casing, of a string of casing, in such a manner as to afford protection for the upper threaded end portion of the casing section. When the upper casing section has been lowered sufficiently to enable 20 the application of another such section, the casing collar attachment of the invention will be displaced and applied to the upper threaded end portion of the newly lowered casing section.

25 At the present time it is customary to resort to a makeshift expedient for the purposes of the invention, it being common practice to "bell out" a short piece of casing on the ground and employ it as a sort 30 of makeshift method of protecting the threads at the upper end of the casing section.

The aim of the invention is to provide 35 a handy device, already constructed, and such as may be readily and quickly applied to the casing section, to afford a greater protection than the means utilized at the present time, also being, of course, a more permanent and effective means for the purposes in view.

40 A full understanding of the invention and its utility will be had upon reference to the following detailed description, in conjunction with the accompanying drawings, 45 in which;

Figure 1 is a view illustrating the method of application of the casing collar embodying the invention, it being understood that the proportions of the parts may be different relatively than those illustrated.

50 Figure 2 is a perspective view of the casing collar alone.

Figure 3 is a section taken about through

the middle of the collar or about at the split portion thereof.

It is contemplated, of course, that an attachment such as the invention proposes shall be of exceedingly simple construction, so as to enable it to be very cheaply manufactured, and yet it is intended to be extremely substantial so as to stand the wear and tear incident to its use in well drilling operations.

Referring to the drawings, a well collar such as our invention contemplates will preferably consist of a body A that may be generally described as being made from a piece of sheet metal folded upon itself to provide spaced side portions, and after the folding, being bent into the shape of a ring 70 or collar. By reason of the foregoing method of construction, our collar body A comprises an outer wall 1 and an inner wall 2. The outer wall 1 may be characterized as a clamping element primarily, and the inner wall 2 as a protective element, adapted to lap over the threads of the upper portion of the casing section, and prevent the mutilation of these threads, something to be prevented, if possible, for obvious 80 reasons.

It is contemplated that our casing collar shall be made of very stout sheet metal and preferably the rim portion of the collar may be thicker or heavier than the main 85 portions of the walls thereof, to reinforce the construction and enable it to withstand the wear and tear to the best advantage.

The collar is of split formation, having its ends spaced apart, but connected by means 90 of offstanding plate lugs 3 to receive a bolt therethru, the plate lugs being riveted preferably to the clamping wall 1 of the device.

Obviously by suitable adjustment of the bolt 4, our casing collar may be readily 95 bolted and firmly clamped in position on the upper end of the casing section, and as readily removed. At the upper portion thereof, the inner wall 2 of the device will be provided with apertures 5 at suitably 100 spaced intervals. These apertures afford exits for mud or foreign matter that may lodge between the walls, and which may be ejected through the openings in an obvious manner.

In area the walls 1 and 2 are substan-

tially co-extensive, and the body A of the device are advantageously made of a single piece of metal. As the clamping effect of the device upon the casing section is derived from the contraction of the outer wall 1 of the same, resulting in practically a reduction in diameter of the inner wall, there is no liability of the scoring of the threads of the casing section in firmly securing the device to the casing element.

It is to be understood that the devices of the invention are to be made in different sizes in order to accommodate for the particular size of casing sections on which it will be used. Furthermore, the several proportions of the device as previously noted may be modified within the purview of the invention, as we do not wish to be limited to the exact construction disclosed in the drawings forming a part hereof. Other simple clamping means might be utilized than that illustrated, and in other particulars the construction may be modified as to slight changes of shape.

Having thus described our invention, what we claim as new and desire to secure by Letters Patent, is:

1. A casing collar for the purpose described, comprising a body composed of inner and outer walls to receive therebetween a threaded member, the threads of which will be protected by one of said walls, and means for securing the said body to such threaded member, one of the said walls being provided with apertures at intervals therein.

2. A casing collar for the purpose described, comprising a body composed of inner and outer walls to receive therebetween a threaded member, the threads of which will be protected by one of said walls, and means for securing the said body to such threaded member, the said walls forming continuations one of the other and being bent into ring like formation so that their ends are juxtaposed, and the securing means comprising a connection between said ends.

3. A casing collar for the purpose described, comprising a double walled body of annular form, the walls being spaced apart to receive therein a threaded element so that one of the walls may protect said element,

and means for contracting said body whereby to secure it firmly to a part to which it is applied. 55

4. A casing collar for the purpose described, comprising a double walled body of annular form, the walls being spaced apart to receive therein a threaded element so that one of the walls may protect said element, 60 and means for contracting said body whereby to secure it firmly to a part to which it is applied, comprising a fastening means for drawing the ends of the body toward each other. 65

5. A casing collar for the purpose described, comprising a double walled body of annular form, the walls being spaced apart to receive therein a threaded element so that one of the walls may protect said element, 70 and means for contracting said body whereby to secure it firmly to a part to which it is applied, comprising a fastening means for drawing the ends of the body toward each other, the inner of said walls 75 being formed with a series of apertures.

6. As a new article of manufacture, a casing collar of the class described, comprising a piece of sheet metal folded upon itself to form spaced walls, and then bent into ring 80 like form so that its ends are juxtaposed, and means for contracting said casing about a part received between the walls thereof.

7. As a new article of manufacture, a casing collar of the class described, comprising a piece of sheet metal folded upon itself to form spaced walls, and then bent into ring 85 like form so that its ends are juxtaposed, and a clamping means for securing the casing to a well casing section and applied to the outer wall of the collar for drawing the ends of the collar together. 90

8. A well casing collar of the class described, comprising a ring like body composed of spaced walls and having the ends 95 thereof juxtaposed, with securing means between said ends and applied to the outer wall of the body for clamping the collar upon a well casing section substantially as described.

In testimony whereof we affix our signatures.

JESS A. MORRISON.
WILLIAM W. HARGROVE.
